UNITED STATES PATENT OFFICE

1,993,208

SHOE

Abraham Cohn, St. Louis, Mo.

Application June 28, 1930, Serial No. 464,538

8 Claims. (Cl. 36—17)

My invention relates, generally, to shoes for men, ladies and children and particularly to an improved construction for Goodyear welt shoes.

The object of my invention is to provide a per-
5 forated elastic filler and a shank and heel stiffener
which are adapted to be interposed between the
insole and outsole of Goodyear welt shoes with
the filler disposed wholly within the inseam and
heel seat cavity of the shoe to set up a combined
10 elastic and pneumatic cushion effect for the en-
tire foot of the wearer of the shoe, and, which
structure will permit the shoe to be assembled and
manufactured upon a production basis in shoe
factories without the necessity of employing
15 special machinery not now used in the manufac-
ture of the present day styles of shoes.

A further object of the invention is the provi-
sion of means adapted to be interposed between
20 the insole and outsole of a Goodyear welt shoe
between the shank and heel sections thereof,
which possesses advantages in points of simplicity
and efficiency, and, at the same time proves itself
comparatively inexpensive in cost of manufac-
ture.

25 With the above and other objects in view, the
invention consists in the novel features of con-
struction, arrangement and combination of parts
hereinafter more fully described and finally
pointed out in the claims hereto appended.

30 Referring to the accompanying drawing form-
ing a part of this specification, wherein like char-
acters of reference denote similar parts through-
out the several views:

Fig. 1 is a view in vertical sectional elevation
35 of the lower portion of a Goodyear welt shoe em-
bodying the features of my invention.

Fig. 2 is a vertical sectional elevation of the
heel and counter section of the shoe taken on lines
2—2 of Fig. 1.

40 Fig. 3 is a top plan view of the shank and heel
stiffener.

Fig. 4 is a bottom plan view of the rubber elastic
filler with a part of the shank and heel stiffener
applied thereto.

45 Fig. 5 is a longitudinal vertical sectional view
of the shank and heel stiffener.

In the drawing, A designates, generally, a shoe
of the type which is known to the trade as a
50 Goodyear welt shoe, and which includes the out-
sole 1, the welt 2, the insole 3 and the upper 4.
The reference numeral 5 designates a cavity
formed upon the insole due to the stitched inseam
6 which unites the insole and welt to the upper.
The cavity 5 known as the inseam and heel seat
55 cavity extends approximately the full length and

width of the insole within the bounds of the
stitched inseam 6 securing the insole and welt
to the upper and within the bounds of the turned
under lower heel edge portion 7 of the counter
portion of the upper which provides the usual heel
seat 8 for the shoe. 5

In carrying out the particular aim of my in-
vention, I cement or similarly secure a resilient
rubber filler B having the shank portion 9 and a
heal portion 10 to the lower face of the insole 3
including the shank and heel portions 9 and 10
thereof, and the filler A is adapted to occupy
only space within the bounds of the aforesaid
inseam and heel seat cavity between the insole 3
and outsole 1 of the shoe. 15

A shank and heel stiffener 11 is provided with
an integral longitudinally and transversely con-
caved-concaved heel plate section 12 and is pref-
erably, although not necessarily provided with a
centralized aperture 13 and the shank and its 20
heal section are formed from suitable gauged
metal, fiber or any other material which may be
found suitable for the purpose intended. I lay
the shank and heel stiffener 11 upon the lower
face of the shank portion 9 of the elastic rubber
filler A and the dished heel portion 12 thereof is
applied to contact with the lower face of the heel
section 10 of the rubber elastic filler, which heel 25
section 10 of the rubber elastic filler is provided
with a centralized thickened portion to provide
a suitably shaped plug or lug extension 14 di-
rected downwardly from the lower face of the
heal portion 10 of the elastic filler, and the lower
end portion of the plug or lug extension 14 is
adapted to be received in the centralized aper-
ture 13 of the heel plate section 12 of the shank
and heel stiffener 11. The shank and heel stiff-
ener 11 is preferably, although not necessarily
nailed, as at 15 to the filler and insole so as to 30
hold it against displacement upon the shank and
heal portions of the rubber elastic filler A to facili-
tate further operations to be performed in the
manufacture of the shoe. It need not necessarily
be nailed in position, as other methods of secur-
ing it to the filler may be employed, such for in-
stance as cementing it thereto or securing it
thereto in any well known equivalent manner
known to the shoe art. 35

After the shank and heel stiffener has been
assembled and secured in position upon the arch
and heel sections 9 and 10 of the rubber elastic
filler A, the outsole 1 is stitched as designated 40
16 to the welt 2 and the heel portion 17 of the
outsole 1 is nailed down into contact with the
heal portion 12 of the shank and heel stiffener 45
50

55

11 and the heel seat 8 of the shoe by means of 5
nails designated 18 driven into the heel seat of
the shoe. After the outsole has been applied to
the shoe, a plurality of heel lifts 19 are secured
in position upon the outer face of the heel por-
tion of the outsole by means of nails 20 and then
a rubber or other suitable heel 21 is applied to
the lifts 19 by means of nails 22 which pass into
the heel seat of the shoe by passing around the
edge of heel plate section 12 of the shank and
heel stiffener 11.

Due to the fact that the shank and heel stiff-
ener of my improved shoe structure extends to
the heel portion of the shoe, and, further due
15 to the fact that the heel section 12 of the shank
and heel stiffener is longitudinally and trans-
versely concaved-convexed and provided with a
central aperture 13 of such shape as to receive
the plug or lug extension 14 of the heel portion
20 10 of the resilient rubber filler A, it will be ob-
served that I provide a shoe structure which will
provide an elastic and pneumatic cushion sole
for the shoe and give an elastic and pneumatic
cushion effect to the ball, the arch and to the
25 heel of the foot of the wearer of the shoe with
the heel of the foot afforded the greater amount
of elastic and pneumatic cushion effect due to
the plug extension of the heel portion of the rub-
ber elastic filler A, which plug extension 14, when
30 either its lower end is receivable in the opening
13, or contacting with the heel section 12 of the
arch and heel stiffener when not apertured, pro-
vides an air space 23 completely surrounding the
plug extension 14 between the heel end 12 of
35 the shank and heel stiffener 11 and the heel por-
tion 10 of the rubber elastic filler A.

In order to lighten the rubber elastic filler and
to afford a pneumatic effect to the sole of the
shoe, as well as an elastic, or resilient effect,

40 I provide the filler A with a multiplicity of ver-
tically disposed punched openings 24, including
the shank and heel sections 9 and 10 thereof,
and I further provide the plug extension 14 of
the heel section 10 of the filler with a plurality
45 of suitable punched vertical openings 25 to pro-
vide a multiplicity of air pockets for the rubber
elastic filler between the insole and outsole
throughout the entire area thereof, as well as the
air pocket 23 surrounding the plug extension 14
50 of the heel portion of the elastic filler.

By inserting the lower end of the rubber elas-
tic plug 14 of the heel portion 10 of the filler A,
in the opening of the dished heel portion of the
55 arch shank, it prevents shifting displacement of
the lower end of the plug extension relative to
the heel portion of the shank and heel stiffener
and the air space surrounding the plug extension
between the heel portion of the filler and the
60 heel portion of the shank and heel stiffener per-
mits the heel portion 10 of the filler to yield
downwardly and the plug extension to expand
radially in yielding under pressure to accom-
modate the shape of the bottom of the heel of
65 the wearer of the shoe and to afford a greater
amount of elastic and pneumatic cushion effect
to the heel of the foot than to the arch and ball
positions thereof, yet affording a substantial cen-
tralized elastic and pneumatic cushion effect
70 to the heel to prevent any uneasiness to the
wearer of the shoe by properly shaping itself
to support the heel of the wearer of the shoe
to make walking and standing non-tiresome to
the foot.

75 The rubber filler of my present invention, it

will be apparent from the illustration, is of uni-
form thickness throughout its entire area ex-
cepting at the plug extension thereof, thus
before being applied to the shoe, its upper and
lower planes are parallel arranged. The lower
5 face of the plug is also preferably flat and par-
allel to the upper and lower planes of the filler
proper. The lower face of the plug extension
being flat establishes a slight air space 26 be-
tween the lower face of the plug extension and
10 the concaved upper face of the heel portion of
the outsole when the lower end of the plug ex-
tension is received in the aperture of the dished
15 heel plate portion of the arch shank. This lower
air space 26 also aids with the air space 23
around the plug extension in allowing the plug
extension to be compressed by heel pressure to
cause the upper plane thereof to readily shape it-
self to the shape of the bottom of the heel of the
20 wearer of the shoe. The same effect is provided
when the heel portion of the shank and heel
stiffener is not provided with a central aperture
to receive the plug extension, as is manifest.

A shoe of the character disclosed, must of
necessity be made in quantity production, hence
25 the simple and practical manner of assembling
has been worked out only through extensive ex-
periments and, as shown, the shoe is considered
by shoe experts a far reaching improvement over
my former Patent Number 1,476,690, which can
30 be made by a cobbler all right, but not under
any circumstances can it be made in quantity
production, as modern shoe machinery cannot
be utilized in the manufacture of the shoe con-
35 structed as disclosed and illustrated in my
former patent.

The many advantages of the herein described
invention will readily suggest themselves to those
skilled in the art to which it appertains.

From the foregoing description, it is evident
40 that a simple device for this purpose has been
disclosed, but it is to be understood that I do not
desire to restrict, or limit myself to the very de-
tails of the construction shown and described,
which is merely illustrative, it being obvious that
45 changes, not involving the exercise of invention,
may be made without conflicting or departing
from the spirit of the invention within the scope
of the appended claims.

What I claim is:

1. In a Goodyear welt shoe construction, a
perforated elastic filler interposed between the
insole and outsole of the shoe including the shank
and heel portions thereof, a perforated central-
55 ized elastic extension directed downwardly from
the lower face of the heel section of the elastic
filler, a metallic plate interposed between the
shank and heel portions of the elastic filler, and
the outsole and the heel portion of the metallic
60 plate being dished to provide an air pocket sur-
rounding the perforated elastic extension of the
elastic filler.

2. In a Goodyear welt shoe construction, a
perforated elastic filler interposed between the
insole and outsole of the shoe including the shank
and heel portions thereof, a centralized elastic
extension directed from the lower face of the heel
portion of the elastic filler, a metallic plate inter-
70 posed between the shank and heel portions of
the elastic filler and the outsole, the heel sec-
tion of the plate being dished to establish an air
space surrounding the elastic extension of the
75 heel portion of elastic filler between the heel por-
tions of the insole and the plate, and said elastic

extension of the heel portion of the elastic filler having a plurality of vertical openings to provide air pockets within the elastic extension and between the heel portions of the insole and said plate.

3. In a Goodyear welt shoe, an elastic rubber filler interposed between the insole and outsole of the shoe including the shank and heel portions thereof, a centralized elastic rubber extension directed from the lower face of the heel portion of the elastic filler, and a metallic plate interposed between the shank and heel portions of the elastic filler and the outsole, the heel section of the plate being dished and provided with a central opening to receive the lower edge portion of the rubber elastic extension of the heel portion of the elastic filler to cause the lower face of the extension to seat upon the upper face of the heel portion of the outsole and to establish an air pocket surrounding the extension between the elastic filler extending beyond the sides of the downward elastic extension of the filler and the dished heel portion of the plate.

4. In combination with a shoe having an outsole and an insole and an inseam and a heel seat cavity therebetween, a resilient rubber filler arranged between the outsole and the insole of the shoe and filling said cavities, said filler including a sole, shank and heel portions each provided with a plurality of punched out openings, a shank and heel stiffener having a central opening in the heel portion thereof and seated upon the outer face of the shank and heel portions of the filler and the heel portion of said filler spanning the opening in the heel portion of the shank and heel stiffener.

5. The combination of a Goodyear welt shoe having a cavity extending from the very toe of the insole to the extreme heel portion thereof, with a flat solid resilient rubber filler seated on the lower face of the insole and completely filling said cavity, said rubber filler having spaced punched out openings throughout its entire area to increase its resiliency and to afford a multiplicity of individual air pockets, a combined shank and heel stiffener having a central opening in the heel portion thereof, said heel portion of the shank and heel stiffener being dished downwardly and a portion of the heel portion of the filler spanning the opening in the heel section of the combined shank and heel stiffener so that the spanning heel portion of the filler will be subject to resilient yielding movement into the said central opening due to heel pressure during walking movements of a person wearing the shoe to afford greater resiliency at the central heel portion of the shoe than at the shank and foot portions thereof.

6. In combination with a Goodyear welt shoe

having an inseam and heel seat cavity between the insole and outsole of the shoe, the heel seat cavity being dished in relation to the inseam cavity, a non-sponge yieldable resilient rubber filler having a sole, shank and heel portion provided with a plurality of individual separated vertical openings positioned in the inseam and heel seat cavities between the insole and outsole of the shoe to provide a plurality of individual air pockets between the insole and outsole, a resilient rubber projection directed downwardly from the central portion of the lower face of the heel portion of the filler and small in relation thereto, and said plug being seated on the dished heel portion of the outsole to provide an annular air chamber between the heel portion of the filler adjacent the projection and the dished heel portion of the outsole.

7. A shoe construction of the Goodyear type comprising, in combination, an upper, a welt, an insole having an inseam and heel seat cavities, an outsole having the heel portion thereof curved downwardly to deepen the heel seat cavity, a non-sponge resilient rubber filler provided with a plurality of individually separated vertical openings, said filler being cemented to the bottom face of the insole and occupying the inseam and heel seat cavities between the insole and outsole of the shoe and an apertured resilient rubber projection small in relation to the heel portion of the filler and directed downwardly from the lower face thereof, said plug being seated on the inner face of the dished heel portion of the outsole to provide an annular air chamber surrounding the rubber projection between the heel portion of the filler adjacent the projection and the dished heel portion of the outsole.

8. A shoe construction of the Goodyear type comprising, in combination, an upper, a welt, an insole having inseam and heel seat cavities, an outsole having the heel portion thereof curved downwardly to deepen the heel seat cavity, a non-sponge resilient rubber filler provided with a plurality of individually separated vertical openings and cemented to the bottom face of the insole to occupy the space formed by the inseam and heel seat cavities between the insole and outsole of the shoe, an apertured resilient rubber plug on the lower face of the heel portion of the filler, and a combined shank and heel stiffener having an opening in the heel portion thereof seated on the bottom face of the shank and heel portions of the filler and the lower edge portion of said resilient rubber plug passing through the opening in the heel portion of the combined shank and heel stiffener and seated on the inner face of the heel portion of the outer sole.

ABRAHAM COHN.
